AUTOMATIC MATERIAL HOLDBACK FOOT
ATTACHMENT FOR SEWING MACHINES

Meyer Unger, Oneonta, N. Y.

Application March 15, 1940, Serial No. 324,181

18 Claims. (Cl. 112—239)

This invention relates to an automatic material hold-back foot attachment for sewing machines.

In garment industries and in the use of sewing machines manually controlled in their operation, it has heretofore been the practice of sewing machine operators when working upon materials subject to stretching activities during the sewing operation and in particular bias sewing, to retard or hold back the feeding of the material rearwardly of the presser foot by holding the material rearwardly of and post-jacent the presser foot to prevent stretching of the material, but such methods offer dangerous hazards to the operators who use their fingers to hold back the material, for it frequently happens that the fingers of the operators are injured by the sewing machine needle. Also by effecting the holding back of the feed of the material being sewed by the foregoing method, there is no assurance that the fingers of the operator can accomplish the desired results because in many instances the retarding pressure exercised by the operator may be unintentionally relieved and result in stretching of the material while being sewed upon.

In the sewing of materials, especially light flimsy materials and in sewing on the bias, there is a tendency by the operator to clear the bed plate or table of the machine of the sewed material rearwardly of the presser foot and this clearing action on the material is accomplished by pushing or shoving the material rearwardly of the presser foot which exerts a strain on the sewed material and stretches the same, especially those materials sewed on the bias. In the sewing of materials of considerable length, the weight of the material passed beyond the presser foot and falling from the bed plate or table of the machine exerts a pulling strain on the sewed material and tends to stretch the same rearwardly of the presser foot.

It is therefore the primary object of this invention to provide an attachment for a sewing machine of any type which may be attached to a sewing machine and be automatically controlled in its operation to hold back the feeding of the material and prevent stretching thereof while being sewed, the attachment being of such character that the same may be rendered inoperative to permit the sewing machine to be used in ordinary sewing operations.

A further object of the invention is to provide an automatic material hold-back foot attachment for sewing machines that is associated with

the usual sewing machine presser foot and positioned post-adjacent thereto, being capable of adjustment with respect to the presser foot and having devices for the operation thereof operatively engaged with a movable element of the usual sewing machine mechanism, the automatic hold-back foot being operative to prevent the free feeding of the material rearwardly of the presser foot and causing the material to be puckered, gathered or bunched between the hold-back foot and the presser foot for a regular number of regular sewing machine stitches with devices operative for automatically raising the hold-back foot to permit the escape of the sewed material with the hold-back foot immediately thereafter lowered into its operative material hold-back position.

It is a further object of the invention to provide an automatically operating material hold-back foot of the foregoing character wherein the tension on the hold-back foot may be varied to accommodate its use with materials of different kinds such as silks, linens, voiles, cottons, rayons, or heavy materials such as woolens or jerseys or the like.

With the above and other objects in view that will become apparent as the nature of the invention is better understood, the same consists in general of certain novel details of construction and combination of parts hereinafter more fully described, illustrated in the accompanying drawings and claimed.

In the accompanying drawings:

Figure 1 is a side elevational view of a sewing machine constructed in accordance with the present invention, the stand being omitted and showing the automatic material hold-back foot attachment therefor.

Figure 2 is a bottom plan view of the sewing machine showing a part of the operating mechanism for the material hold-back foot.

Figure 3 is an outer end elevational view of the head of the sewing machine showing the vertically reciprocating needle, the vertically adjustable presser foot, and the vertically movable automatic material hold-back foot attachment, the latter being illustrated as variably tensioned and the device for holding the hold-back foot elevated in inoperative position.

Figure 4 is a vertical cross sectional view taken on line 4—4 of Figure 1, showing a part of the operating mechanism for effecting a step-by-step movement of devices to permit a predetermined number of stitches to be sewed before

the material hold-back foot is elevated to its material releasing position.

Figure 5 is a fragmentary longitudinal sectional view taken on line 5—5 of Figure 4.

Figure 6 is a detailed cross-sectional view taken on line 6—6 of Figure 5, showing a brake device permitting rotary movement of one of the clutch elements in one direction only.

Figure 7 is a detailed sectional view taken on line 7—7 of Figure 5, showing a brake or clutch device permitting movement of the other clutch element in one direction only.

Figure 8 is a fragmentary outer end elevational view of the head of the sewing machine with the automatic material hold-back foot in its lowered, operative position and showing the sewed material gathered between the presser foot and the hold-back foot.

Figure 9 is a fragmentary elevational view, similar to Figure 8, showing the material hold-back foot elevated with the gathered or bunched material projected rearwardly thereof and in semi-gathered formation, and

Figure 10 is a fragmentary elevational view, partly in section, of the material hold-back foot and the supporting guide therefor.

Referring more in detail to the accompanying drawings, a sewing machine of standard construction is illustrated and comprises a bed plate 15 from one end of which rises the usual hollow upright 16 that carries at its upper end a horizontally extending overhanging hollow arm 17 that carries at its free end above the bed plate 15 a head 18. A horizontal drive shaft 19 extends through the upper end of the upright 16 and the overhanging arm 17, one end of the drive shaft projecting from the upper end of the upright and carrying the usual fly wheel 20 and drive belt sheave 21, the other end of the drive shaft 19 being operatively engaged with the vertically sliding bar 22 in the head 18 that carries the needle 23 at its lower end. The vertically sliding bar 24 in the head 18 carries the presser foot 25 at its lower end that engages the throat plate 26 of the bed plate 15, these devices being common to sewing machines of standard construction. The vertically movable bar 24 that carries the presser foot 25 at its lower end has a laterally directed abutment adjacent its upper end as shown at 27, said abutment projecting outwardly of the head 18 as shown in Figure 3 for engagement by the cam lever 28 pivotally mounted upon the stub shaft 29 having a threaded end 30 to facilitate mounting of the shaft in the head 18.

The automatically operating material hold-back foot attachment for the sewing machine as shown more clearly in Figures 1, 3 and 8 to 10 comprises a vertically shiftable rod 31 vertically slidable in the tubular guide 32 carried by the stub shaft 29 and extending across the end of the latter, the rod 31 carrying a cross pin 33 having projecting ends extending through diametrically opposite slots 34 in the upper end of the tubular guide 32 to restrain rotative movements of the rod 31 in the tubular guide but permitting sliding movements thereof. The lower end of the rod 31 is threaded as at 35 for the adjustable threaded reception of the material hold-back foot 36 retained in adjusted position thereon by means of the set screw 37. As shown in Figure 3, the hold-back foot 36 is post-jacent the presser foot 25, and while illustrated as being directly aligned therewith, it is to be understood that angular adjustments of the hold-back foot rela-

tive to the presser foot may be made. It will also be observed that a pocket area 36a is formed between the rear end of the presser foot 25 and the forward end of the hold-back foot 36 which permits the gathering of the material being sewed therein. A support is provided for the upper end of the rod 31, and to vary the tension of the hold-back foot 36 in its engagement with the material, the rod 31 below the lower end of the tubular guide 32 is surrounded by a coil spring 38, the upper end of which engages the lower end of the tubular guide while the lower end of the spring is engaged by a nut 39 adjustably threaded on the lower end of the rod 31.

The supporting means for the upper end of the rod 31 of the hold-back foot is shown more clearly in Figure 1 and comprises a lever arm pivotally mounted as at 40 on the outer side of the overhanging arm 17, one end 41 of the lever arm extending toward the head 18, while the other end 42 extends toward the upright 16. The free end of the lever arm 41 carries an end extension pin 43 that freely passes through a slotted opening 44 in a head 45 at the upper end of the rod 31 as shown in Figures 1 and 3. The free end of the lever arm 42 has pivotally connected thereto as at 46 the upper end of a link rod 47, with the lower end of the link rod 47 as shown more clearly in Figures 1, 4 and 6 being bent at right angles to provide a hook 48 that is pivotally engaged with one end of the lever 49 pivoted intermediate its ends as at 50 on a lug 51 depending from the bed plate 15, the lever 49 being adapted for operation by the knee of the operator for moving the lever arms 41 and 42 for the elevation of the material hold-back foot 36 when it is desired to manually raise the same. The link rod 47 is normally held at its limit of upward movement while the rod 31 carrying the hold-back foot 36 is normally held at its limit of downward movement by means of the coil spring 38 interposed between the stationary tubular guide 32 and the nut 39 adjustable on said rod 31. When the presser foot 25 is elevated from the throat plate 26 by the cam lever 28, the abutment shoulder 25a on the upper end of the presser foot 25 engages the nut 39 upon the rod 31 to elevate the hold-back foot 36 therewith so that the material may be properly placed beneath the presser foot 25 and the hold-back foot 36 at the desired point. When it is desired to use the sewing machine to the exclusion of the automatic material hold-back foot attachment, the rod 31 carrying the hold-back foot is elevated against the tension of the spring 38 and is so held by the latch 52 shown more clearly in Figures 1 and 3 as being pivoted at one end as at 53 on the head 18 with an operating handle 54 carried by its other end, the latch 52 being engageable with the underside of the pin extension 43 carried by the lever arm 41 for elevating the latter as will at once be apparent from an inspection of said figures.

In standard constructions of sewing machines, the drive shaft 19 is operatively engaged with a series of rocker shafts and other shafts for the operation of the vertically reciprocating bar 22 carrying the needle, the material feeding shoe and also for the shuttle 55 disposed beneath the throat plate 26, rocker shafts being indicated in Figures 2, 4 and 5 by the reference characters 56 and 57, the rotatable shaft 58 operating the shuttle 55. Mechanism for the automatic operation of the hold-back foot attachment is illustrated as operatively engaged with the rocker

shaft 57, the latter having a laterally directed arm 57^a shown in Figure 2, to the outer end of which a link rod 59 is pivotally attached as at 59^a, the link rod 59 being fragmentarily illustrated in Figures 4 and 5 with the other end of the link rod operatively connected to the drive shaft 19. A bracket plate 60 is illustrated as being vertically disposed and extending transversely subjacent the bed plate 15 and carries at its upper end a horizontal flange 61 that is bolted as at 62 to the bottom face of the bed plate 15, the bracket plate 60 providing a support for the operating devices for the material hold-back foot. A shaft 63 extends longitudinally of the bed plate 15 through the bracket plate 60, the latter carrying a support 64 at one side thereof for said shaft 63 with the shaft anchored in the support against rotation as at 65. A clutch device is associated with the shaft 63 at the side thereof opposite the support 64 and said clutch device includes a collar 66 rotatable on the shaft 63 latero-jacent the bracket plate 60, the collar 66 carrying a peripherally projecting cam lug 67. A clutch disk 68 rotatable on the shaft 63 has an interfitting abutting connection with the collar 66 and is secured thereto by the radial screw pins 69. A cooperating clutch disk 70 has an interfitting facial connection with the clutch disk 68, said interfitting connection comprising overlapping shoulders 71 and 72 as clearly shown in Figure 5. The outer face of the clutch disk 70 is provided with a transversely extending undercut groove 73 and said clutch disk 70 is maintained in assembled relation with the clutch disk 68 by means of the headed end screw 74 threaded through the bottom wall of the undercut groove 73 and entering the adjacent end of the shaft 63.

As shown more clearly in Figure 7, the shoulered portion 71 of the clutch disk 70 is provided with a cam groove or pocket 75 facing the uninterrupted peripheral surfaces of the shoulered portion 72 of the clutch disk 68, the cam pocket 75 housing a ball or roller 76 to provide binding or wedging engagement between the clutch disks 68 and 70 when said clutch disk 70 is rotated in one direction relative to the clutch disk 68. A wedging device or break is also associated with the clutch disk 68 to permit rotation thereof in one direction and to restrain rotation in the opposite direction and, as shown in Figure 6, comprises a holder 77 mounted upon the bracket plate 60, the holder 77 supporting a wedge plate 78 with a ball or roller 79 interposed between the wedge plate 78 and the peripheral surface of the clutch disk 68, said wedging ball or roller 79 being retained in its operative position as illustrated in Figure 6 by means of a cover 80 secured to the holder 77, said cover 80 having an opening therein housing a coil spring engaged with the ball or roller 79 and in turn engaged by the screw 81 threaded through the outer end of the cover 80.

Oscillatory movements are imparted to the clutch disk 70 through operative connections with the rocker shaft 57 which include, as shown in Figures 2 and 4, an arm 82 fixed at one end to the rocker shaft 57 with the arm extending across the outer face of the clutch disk 70 and being longitudinally slotted as at 83 with a pin 84 that is radially adjustably mounted in the undercut groove 73 extending into said slot.

As shown more clearly in Figures 4 and 6, a screw pin 85 is secured in the bracket plate 60 and pivotally supports a bell-crank lever having

lever arms 86 and 87, the lever arm 86 having its free end disposed in the path of rotary movement of the cam lug 67 on the collar 66 while the outer end of the other lever arm 87 has an opening therein for the passage of a rod 88, the lower end of which is threaded as at 89 for the reception of the thumb nut 90 that is engaged with the lower side of the lever arm 87, while the upper end of the rod 88 carries a hook 91 for engagement with the hook 48 at the lower end of the link rod 47. By adjusting the nut 90 on the rod 88, the effective position of the free end of the lever arm 86 relative to the cam lug 67 may be varied, different adjustments providing for the degree of vertical lift of the material hold-back foot 36 to compensate for different thicknesses of material being sewed.

From the above detailed description of the invention, it is believed that the construction and operation thereof will at once be apparent, it being noted that during the operation of the sewing machine with the material hold-back foot lowered into material-engaging position as shown in Figure 8, the material feed with the feed dog beneath the presser foot is held back by said foot 36 to the exclusion of the hands of the operator, the material being illustrated in Figure 9 by the reference numeral 95 as entering beneath the presser foot 25 while the stretched or sewed material is illustrated in Figure 8 in a gathered or bunched condition as at 95^a within the pocket 36^a between the presser foot 25 and the hold-back foot 36. This action of the hold-back foot 36 relieves any pulling strains on the material 95 and eliminates the practice of the operator using the fingers of the hand to retard the feeding of the material, the hold-back foot 36 being operative to prevent stretching of the material, especially light flimsy materials or materials that are being sewed on the bias. During the operation of the sewing machine the rocker shaft 57 imparts a swinging movement to the slotted arm 82 and said arm 82 oscillates the clutch disk 70 as will be apparent from an inspection of Figure 4, this motion of the clutch disk 70 is imparted to the clutch disk 68 through the medium of the cam pocket 75 and the wedging ball or roller 76 shown therein in Figure 7, one rotary direction of movement of the clutch disk 70 carrying the clutch disk 68 in a like direction of rotary movement, the wedging devices 75 and 76 preventing rotary movement of the clutch disk 70 in the opposite direction relative to the clutch disk 68. To prevent retrograde rotation of the clutch disk 68, the wedging device 79 shown in Figure 6 is engaged with said clutch disk 68, but is operative to permit rotary movement in one direction of the clutch disk 68 under influence of the clutch disk 70. The rocker shafts and the driving shaft 19 for the needle carrying bar 22 are so timed that with each reciprocation of the needle shaft for the sewing of a stitch effects one step rotary movement of the collar 66 fixed to the clutch disk 68 and after a predetermined number of stitches have been sewed the cam lug 67 upon the collar 66 moves into engagement with the bell-crank lever arm 86 for pulling downwardly on the rod 88 by means of the lever arm 87, the link rod 47 for operating the two-armed lever 41-42 for the elevation of the rod 31 carrying the material hold-back foot 36. When the hold-back foot 36 is elevated as shown in Figure 9, the bunched material illustrated at 95^a in Figure 8 automatically escapes through inherent tension in the bunched material and assumes the gathered formation 95^b shown

in Figure 9. This gathered formation is serviceable in uniting bias and similar seams, especially in arm-hole work on garments and if the gathering formation 95^b is not desired, the material may be easily flattened and restrained against stretching activities by the line of stretching in the material. The number of stitches sewn between the rise and fall of the hold-back foot 36 may be varied by adjusting the pin 84 longitudinally of the clutch disk groove 73 and the slot 83 in the arm 82, the tension of the hold-back foot 36 being adjusted by the nut 39 on the rod 31, the angularity of the hold-back foot being adjustable relative to the presser foot 25 while the degree of lift of the hold-back foot 36 is adjusted by means of the nut 90 shown in Figures 4 and 6 as threaded upon the lower end of the rod 88 that has its upper end engaged with the link rod 47.

When the cam lever 28 is operated for raising the presser foot 25, the hold-back foot 36 is automatically raised therewith and when it is desired to use the sewing machine to the exclusion of the hold-back foot, the latch 52 engages the pin 43 at the free end of the lever arm 41 to elevate the rod 31 carrying the hold-back foot 36. The hold-back foot 36 may be elevated by means of the knee-operated lever 49.

While there is herein shown and described the preferred embodiment of the invention, it is to be understood that various changes may be made therein, such as will come within the scope of the invention as claimed, it being further understood that the mechanism disclosed herein is only one embodiment of the invention to accomplish the automatic hold-back of the material while being sewed upon to prevent stretching activities of the material and to prevent injury to the hands of the sewing machine operators.

I claim:

1. In combination with a sewing machine having the usual sewing needle and presser foot and reciprocating carrying bars therefor, operating means for the bar carrying the needle, an automatically operated material hold-back foot postjacent the presser foot and normally positioned to prevent passage of material passed rearwardly of the presser foot and means operated at intervals following a predetermined multiple number of reciprocatory movements of the bar carrying the needle to raise the hold-back foot to release the held material.

2. In an automatic material hold-back foot attachment for sewing machines, wherein the sewing machine includes a presser foot having an associated cam lifting lever, a material feeding dog and operating means for the dog, said attachment including a tensioned hold-back foot postjacent the presser foot and normally lying in the operative plane of the presser foot to hold back and prevent stretching of the sewed material passed rearwardly of the presser foot and devices interposed between the tensioned hold-back foot and said operating means and operated by the latter to effect raising of the hold-back foot at predetermined intervals following a predetermined multiple number of reciprocatory movements of the bar carrying the needle to raise the hold-back foot to release the sewed material held back by said tensioned hold-back foot.

3. An automatic material hold-back foot attachment for sewing machines as set forth in claim 2, wherein a vertically shiftable rod carries the hold-back foot and said devices include

a series of links and levers with one end of a lever engaged with the upper end of the rod.

4. An automatic material hold-back foot attachment for sewing machines as set forth in claim 2, wherein a vertically shiftable rod carries the hold-back foot and said devices include a series of links and levers with one end of a lever engaged with the upper end of the rod, and an obstruction on said rod adapted to be engaged by said presser foot whereby the hold-back foot may be manually raised when the cam lever is operated for raising the presser foot.

5. An automatic material hold-back foot attachment for sewing machines as set forth in claim 2, wherein a vertically shiftable rod carries the hold-back foot and said devices include a series of links and levers with one end of a lever engaged with the upper end of the rod and means for holding the hold-back foot in elevated inoperative position.

6. An automatic material hold-back foot attachment for sewing machines as set forth in claim 2, wherein a vertically shiftable rod carries the hold-back foot and said devices include a series of links and levers with one end of a lever engaged with the upper end of the rod, and an obstruction on said rod adapted to be engaged by said presser foot whereby the hold-back foot may be manually raised when the cam lever is operated for raising the presser foot and means for holding the hold-back foot in elevated inoperative position.

7. An automatic material hold-back foot attachment for sewing machines as set forth in claim 2, wherein said devices include adjustable means to vary the height of raising movement of the material hold-back foot.

8. An automatic material hold-back foot attachment for sewing machines as set forth in claim 2, wherein said devices include clutch elements operative in one oscillatory rotative direction of travel, a cam lug carried by one of said clutch elements, a series of links and levers with one end of a lever connected to the hold-back foot and the end of another lever being in the path of said cam lug for operation thereby to raise the hold-back foot.

9. An automatic material hold-back foot attachment for sewing machines as set forth in claim 2, wherein said devices include clutch elements operative in one oscillatory rotative direction of travel, a cam lug carried by one of said clutch elements, a series of links and levers with one end of a lever connected to the hold-back foot and the end of another lever being in the path of said cam lug for operation thereby to raise the hold-back foot and means for varying the effective operative movement of said series of links and levers to vary the height of raising movement of the material hold-back foot.

10. In an automatic material hold-back foot attachment for sewing machines, wherein the sewing machine includes a presser foot, a material feeding dog and operating means for the dog, said attachment including a tensioned hold-back foot postjacent the presser foot and normally lying in the operative plane of the presser foot to hold back and prevent stretching of the sewed material passed rearwardly of the presser foot and devices interposed between the tensioned hold-back foot and said operating means and operated by the latter to effect raising of the hold-back foot at predetermined intervals to release the sewed material held back by said tensioned hold-back foot, and means for varying the

intervals at which the hold-back foot is raised for the release of the sewed material including a slotted arm having one end fixed to said operating means and a pin radially adjustably secured to an oscillatory element of said devices and extending into the slot of said arm.

11. An automatic material hold-back foot attachment for sewing machines as set forth in claim 2, wherein a vertically shiftable rod carries the hold-back foot and said devices include a series of links and levers with one end of a lever engaged with the upper end of the rod and means for varying the intervals at which the hold-back foot is raised for the release of the sewed material including a slotted arm having one end fixed to said operating means and a pin radially adjustably secured to an oscillatory element of said devices and extending into the slot of said arm.

12. An automatic material hold-back foot attachment for sewing machines as set forth in claim 2, wherein a vertically shiftable rod carries the hold-back foot and said devices include a series of links and levers with one end of a lever engaged with the upper end of the rod, and an obstruction on said rod adapted to be engaged by said presser foot whereby the hold-back foot may be manually raised when the cam lever is operated for raising the presser foot and means for varying the intervals at which the hold-back foot is raised for the release of the sewed material including a slotted arm having one end fixed to said operating means and a pin radially adjustably secured to an oscillatory element of said devices and extending into the slot of said arm.

13. An automatic material hold-back foot attachment for sewing machines as set forth in claim 2, wherein a vertically shiftable rod carries the hold-back foot and said devices include a series of links and levers with one end of a lever engaged with the upper end of the rod and means for holding the hold-back foot in elevated inoperative position, and means for varying the intervals at which the hold-back foot is raised for the release of the sewed material including a slotted arm having one end fixed to said operating means and a pin radially adjustably secured to an oscillatory element of said devices and extending into the slot of said arm.

14. An automatic material hold-back foot attachment for sewing machines as set forth in claim 2, wherein a vertically shiftable rod carries the hold-back foot and said devices include a series of links and levers with one end of a lever engaged with the upper end of the rod, and an obstruction on said rod adapted to be engaged by said presser foot whereby the hold-back foot may be manually raised when the cam lever is operated for raising the presser foot and means for holding the hold-back foot in elevated inoperative position, and means for varying the intervals at which the hold-back foot is raised for the release of the sewed material including a slotted arm having one end fixed to said operating means and a pin radially adjustably secured to an oscillatory element of said devices and extending into the slot of said arm.

15. An automatic material hold-back foot at-

attachment for sewing machines as set forth in claim 2, wherein said devices include adjustable means to vary the height of raising movement of the material hold-back foot and means for varying the intervals at which the hold-back foot is raised for the release of the sewed material including a slotted arm having one end fixed to said operating means and a pin radially adjustably secured to an oscillatory element of said devices and extending into the slot of said arm.

16. An automatic material hold-back foot attachment for sewing machines as set forth in claim 2, wherein said devices include clutch elements operative in one oscillatory rotative direction of travel, a cam lug carried by one of said clutch elements, a series of links and levers with one end of a lever connected to the hold-back foot and the end of another lever being in the path of said cam lug for operation thereby to raise the hold-back foot, and means for varying the intervals at which the hold-back foot is raised for the release of the sewed material including a slotted arm having one end fixed to said operating means and a pin radially adjustably secured to an oscillatory element of said devices and extending into the slot of said arm.

17. An automatic material hold-back foot attachment for sewing machines as set forth in claim 2, wherein said devices include clutch elements operative in one oscillatory rotative direction of travel, a cam lug carrier by one of said clutch elements, a series of links and levers with one end of a lever connected to the hold-back foot and the end of another lever being in the path of said cam lug for operation thereby to raise the hold-back foot, means for varying the effective operative movement of said series of links and levers to vary the height of raising movement of the material hold-back foot, and means for varying the intervals at which the hold-back foot is raised for the release of the sewed material including a slotted arm having one end fixed to said operating means and a pin radially adjustably secured to an oscillatory element of said devices and extending into the slot of said arm.

18. In an automatic material hold-back foot attachment for sewing machines, wherein the sewing machine includes a needle carry bar, a presser foot, a material feeding dog and operating means for the dog, said attachment including a tensioned foot postjacent the presser foot and normally lying in the operative plane of the presser foot to hold back and prevent stretching of the sewed material passed rearwardly of the presser foot and devices interposed between the tensioned foot and said operating means and operated by the latter to effect raising of the hold-back foot at predetermined intervals following a predetermined number of reciprocatory movements of the bar carrying the needle to release the sewed material held back by said tensioned foot, said devices including manually operable means for raising the hold-back foot independently of the presser foot.
